UNITED STATES PATENT OFFICE.

FRANK PARDEE, OF HAZLETON, PENNSYLVANIA, ASSIGNOR TO ANTHRACITE SEPARATOR COMPANY, A CORPORATION OF PENNSYLVANIA.

SPIRAL SEPARATOR.

Application filed October 11, 1921. Serial No. 507,109.

To all whom it may concern:

Be it known that I, FRANK PARDEE, a citizen of the United States, and resident of Hazleton, Pennsylvania, have invented certain new and useful Improvements in Spiral Separators, of which the following is a specification.

This invention relates to spiral separators for handling various classes of lump material but particularly adapted for separating coal from impurities such as slate, rock, etc., which come to the separator in a mixture from the coal breaker.

One object of the invention is to provide a spiral separator having a series of closely arranged ridges adapted to jointly support the lumps of material while on their journey along the runway. Another object is to provide a spiral runway formed with ridges arranged to exert an edge resistance or friction on the material travelling thereon. A further object is to provide ridges so shaped that they control the direction of travel of the materials handled. Other objects will be apparent from the following description when read in connection with the accompanying drawings, in which—

Fig. 1 is a view of a three-quarter turn of one thread of a spiral separator illustrating one embodiment of the invention;

Fig. 2 is a plan showing one turn of the separator thread shown in Fig. 1;

Fig. 3 is an enlarged section on line 3—3 of Fig. 2;

Figs. 4 to 12 inclusive are details of detachable sections or plates of different styles adapted to be used on the separator;

Figs. 13 and 14 are views similar to Figs. 1 and 2 showing an alternative structure;

Figs. 15 to 25 are detail views showing the corrugated jackets of which the separator runway is constructed, the sectional views being taken on the correspondingly numbered section lines of the other views.

Referring first to the embodiment of the invention illustrated in Figs. 1 to 3, the separator includes a central supporting post 1 which carries a number of upwardly inclined radially extending supporting rods 2. The rods 2 are spirally arranged and form supports for the multiplicity of segmental plates or jackets 3 which collectively constitute the spiral floor or runway of the separator thread. The jackets 3 overlap each other along their adjacent radial edges and

are secured to the supporting rods by screws or bolts 4 preferably having countersunk heads so as not to interfere with the travel of the material on the separator. Certain of the jackets are corrugated to form a series of closely arranged ridges 5, and other jackets 3^a for example, are smooth and have detachable sections 6 mounted thereon which are corrugated to form ridges 7, these sections being interposed between the overlapping portions of the jackets as shown in Fig. 1.

Fig. 3 shows best the ridges which are located close to one another, so that a given lump of coal L or other material rides on, or is supported by two or more ridges in its journey along the spiral runway. In other words, the surface of certain parts of the runway is interrupted by the ridges and each lump straddles two or more of the ridges. The edges or peaks of the ridges therefore exert what may be called an edge resistance or edge friction on the material.

The runway may be formed of a series of alternately arranged corrugated sections 3 and plain sections 3^a having detachable sectional covers 6 secured thereto as shown in Fig. 2 or all of the jackets may be corrugated as shown in Figs. 13 and 14.

The ridges on the jackets may be straight and inclined inwardly and downwardly as in Figs. 1 and 2, or they may be concentric with the axis of the separator as shown in Figs. 13 and 14. The corrugated detachable sections 6 can be shaped or proportioned to cover different areas of the surface of the jackets 3^a and the ridges may be either curved or straight and arranged to extend in different directions as shown in Figs. 4 to 12, so as to assist in controlling the frictional effect and the direction of travel of the material along different portions of the runway.

Figs. 15 to 24 illustrate various ways in which the runway jackets may be corrugated to suit different classes of coal or other materials. In Figs. 15 and 16 the jacket is corrugated to form a series of ridges 5 which are substantially concentric with the axis of the separator, the ridges being of uniform height.

Fig. 17 illustrates a jacket in which the ridges are substantially concentric with an axis located beyond the outer edge of the jacket.

Fig. 18 shows a pair of adjacent jackets 110

corrugated to form substantially parallel ridges curved in plan on involute curves and adapted to exert friction on the slaty and other waste materials and direct them to an inner path on the runway.

Figs. 20 and 21 show a pair of adjacent jackets in which the ribs 5 are grouped in rows 8 spaced apart from one another, the rows on one jacket being staggered with respect to those on the adjacent jacket.

Figs. 22 and 23 show a further variation of the jacket in which the inner ridges 5^a are higher than the outer ones 5^b.

Figs. 24 and 25 show the reverse arrangement in which the outer ridges 5^c are higher than the inner ones 5^a, the intermediate ridges being uniformly graded in size and height.

From the above it will be seen that I have devised an improved form of runway for coal separators and the like, and that I can construct the ridges in various conformations to suit the various classes of coal or other materials handled. It is known to those skilled in this art that coal from one vein often requires different treatment from that of other veins and it is apparent that utilizing one or a combination of several of the types of corrugated jackets herein described I can readily adapt the separator for handling materials of widely differing natural characteristics.

While I have particularly described and shown certain specific embodiments of my invention it is not to be interpreted that I am limited to such structures as changes in arrangement and substitution of equivalents may be made without departing from the spirit and scope of the invention as defined in the appended claims.

What I claim is:

1. A spiral separator having a runway formed with a series of ridges adapted to exert an edge resistance on the material travelling thereon, said ridges being spaced so close together that the lumps of material travel on the peaks of two or more adjacent ridges.

2. A spiral separator runway including a plurality of jackets each formed with a series of closely grouped ridges adapted to jointly support the lumps on the peaks of the ridges and exert an edge friction on the lumps of material travelling on the runway.

3. A spiral separator including a runway comprising a plurality of jackets of substan-

tially triangular form, certain of said jackets having a series of closely grouped integral ridges formed thereon, said ridges being spaced close to one another so that the lumps can straddle the same and travel on the peaks thereof, and other smooth jackets having detachable sections secured thereto which partially cover them, said detachable sections also having closely grouped ridges formed thereon the ridges of the jackets and detachable sections being adapted to exert an edge resistance on the lumps of material travelling on the runway.

4. A spiral separator including a runway formed of a series of jackets having groups of closely arranged ridges thereon to form an interrupted supporting surface which the individual lumps travelling thereon straddle, said interrupted surface being arranged to exert an edge resistance on the lumps travelling over the runway, some of said ridges being curved in plan to control the direction of travel of the material.

5. A spiral separator including a runway formed of a series of jackets corrugated to form a multiplicity of closely spaced integral adjacent ridges which jointly form a support for the individual lumps of material travelling on the runway and which jointly exert a frictional resistance on the individual lumps.

6. A spiral separator including a runway formed of a plurality of jackets having closely spaced ridges formed thereon to jointly support individual lumps of material travelling on the peaks of the ridges, the ridges on certain jackets being arranged differently than those on other jackets to produce different degrees of frictional resistance on the individual lumps of material travelling on the runway at different locations thereof.

7. A spiral coal separator comprising a central supporting post having a series of upwardly inclined radial supporting rods secured thereto, a plurality of segmental sheet metal jackets corrugated to form a series of closely spaced ridges adapted to jointly support individual lumps of material travelling thereon so that the edges of a plurality of ridges exert a frictional drag on each individual lump to control its direction of travel.

In witness whereof, I have hereunto signed my name.

FRANK PARDEE.
